REFRIGERATOR CABINET

John H. Ashbaugh, Longmeadow, Mass., assignor
to Westinghouse Electric & Manufacturing
Company, East Pittsburgh, Pa., a corporation
of Pennsylvania

Application September 4, 1941, Serial No. 409,485

11 Claims. (Cl. 62—89)

This invention relates to refrigerator cabinets and more especially to the arrangement of imperforate shelves therein.

Imperforate shelves in domestic refrigerators are desirable because of the decreased dehydration of foods stored in uncovered dishes in refrigerators equipped with such shelves. Imperforate shelves of transparent glass are additionally desirable because of the unobstructed view afforded to the contents of the refrigerator and because of the ease with which glass shelves are cleaned. Imperforate shelves, however, have not been generally used in domestic refrigerators because they unduly obstruct the convectional circulation of air therein so that the portions of the refrigerator at a distance from the cooling unit are not properly cooled. Where such shelves have been used, either special means have been employed for refrigerating the areas at a distance from the cooling unit or very large air-circulating openings around or through the shelves have been provided which unduly reduce the storage space on the shelf.

It is an object of the invention to provide a refrigerator having imperforate shelves and having relatively small air-circulating openings.

Another object of the invention is to provide imperforate shelves in domestic refrigerator cabinets, which shelves provide a maximum of shelf space and a minimum of obstruction to the air circulation through the cabinets.

A further object of the invention is to provide transparent shelves in domestic refrigerator cabinets which do not unduly obstruct the air circulation in the cabinets.

These and other objects are effected by my invention as will be apparent from the following description and claims taken in connection with the accompanying drawing, forming a part of this application, in which:

Fig. 1 is an elevation of a domestic refrigerator with the door thereof opened to an angle of 90 degrees;

Fig. 2 is a section on the line II—II of Fig. 1 with the door in the closed position;

Fig. 3 is a section on the line III—III of Fig. 1 with the door in the closed position; and

Fig. 4 is similar to Fig. 3 but shows a modification of the invention.

Referring to the drawing for a detailed description of the invention, the reference numeral 10 designates a domestic refrigerator comprising a rectangularly-shaped food-storage chamber 11 in the upper portion thereof and a machine compartment 12 in the lower portion. The food com-

partment 11 comprises an inner liner 13 of metal and an outer shell 14 spaced from the top and the side walls of the food liner 13 and continued downwardly thereof to enclose the machine compartment 12. The inner liner 13 and shell 14 form flat vertical side walls 6, a rear wall 7 and a horizontal top wall 8. A partition 15 spaced from the lower wall of the food-storage compartment forms a division wall between the machine compartment 12 and the food-storage chamber 11. Loose heat-insulating material 17 is packed around the inner liner 13 to fill the space between the inner liner 13 and the outer shell 14 and partition 15. The entire front of 15 the food-storage chamber 11 is open to provide access thereto, and the edge adjacent the opening of the inner liner 13 is turned outwardly and the edge of the outer shell 14 is turned inwardly to form attachment flanges for breaker strips 18 which surround the access opening.

The opening of the food-storage chamber is closed by a door 19 which forms the front wall thereof when the door 19 is closed. The door 19 comprises an outer dished shell 21 of metal and an inner panel 22 of rigid heat-insulating material. The edges of the outer shell 21 are turned inwardly and secured to the edges of the inner panel 22 to form a hollow door structure, the interior of which is filled with loose heat-insulating material 23. A sealing gasket 24 is secured at the outer edge of the door and makes contact with the breaker strips 18 when the door 19 is closed. The door 19, side walls 6, back wall 7 and horizontal walls 15 and 8 form the generally rectangular food-storage compartment having four vertically-extending corners 16.

An evaporative cooling unit 26 is secured centrally in the upper portion of the food-storage chamber 11. The cooling unit 26 comprises two refrigerant-carrying side walls 27, a refrigerant-carrying bottom wall 28, and a refrigerant-carrying shelf 29 in the upper portion of the cooling unit 26. A door 31 closes the front wall of the cooling unit 26 and a plate forms the upper wall 32 thereof. The door 31 is preferably not airtight. The area between the upper wall 32 and the refrigerated shelf 29 at the rear of the cooling unit 26 is closed by a plate 33. The rear portion of the evaporator below the refrigerant-carrying shelf 29 is open and a shelf 34 is located in the lower portion of the cooling unit 26. The rear portion of the cooling element 26 is, therefore, in better heat-conducting relationship with the air in the food-storage compartment than the

front thereof. A condensate tray 36 is supported below the cooling unit 26.

A number of generally-rectangular glass shelves 37 are supported below the cooling unit 26 in the food-storage compartment 11 and another glass shelf 38 forms the cover of a vegetable-storage chamber 39. The side edges 41 of the shelves 37 are located closely adjacent the side walls of the inner liner but the rear edges 42 and the front edges 43 of the shelves 37 are spaced from the rear wall of the food liner 13 and from the inner panel 22 of the door 19, respectively, to provide narrow air passages.

In an insulated cabinet of the character described, the greatest heat leakage occurs at the cabinet door and principally at the joint between the cabinet and the door. This heat leakage raises the temperature of the air adjacent the door 19, and the air will rise upwardly through the spaces between the edges 43 of the shelves 37 and the door 19. The relatively warm air will flow rearwardly across the cooling unit 26 and will be cooled. A portion of the air will enter at the upper portion of the opening in the rear of the cooling unit 26, will be cooled to a low temperature therein, and thereupon flow out at the lower portion of the opening in the rear of the cooling unit 26 and down the spaces between the rear edges 42 of the shelves 37 and the rear wall of the inner liner 13. The air will thereafter flow below shelves 37 toward the door 19 and will again be warmed and repeat its circulating cycle. The arrows in Fig. 2 depict the air circulation described.

It will be observed that the air passages are located in the path of the natural convectional air currents in the refrigerator, and for this reason adequate cooling of the lower portion of the food-storage chamber is secured even though the passages are relatively narrow. In practice, it has been found advisable to make the air passages at the rear edges 42 of the shelves 37 somewhat larger than those at the front edges 43 because the air passages at the rear are more likely to become partially obstructed by materials on the shelf being pushed back against the rear wall of the food-storage chamber.

In a comparative test of a refrigerator containing glass shelves shaped according to the modification shown in Fig. 3 and a similar refrigerator equipped with open wire shelves, it was found that with two glass shelves each having an area of 407 square inches and air passages of 13½ square inches at the front edge of each shelf and 27 square inches at the rear edge thereof, the temperature below the lowest shelf was approximately 2° F. higher and the temperature above and near the top shelf was approximately 2° F. lower in the refrigerator equipped with glass shelves than in the one equipped with wire shelves. The incidental air spaces at the side edges of the glass shelves were 5¼ square inches at each edge. During the test, the shelves were loaded with comestibles representing average conditions of service.

A more effective location of the air-circulating passages in the food-storage compartment is shown in the modification illustrated by Fig. 4. In this modification, the central portion of the front edges 47 of the shelves 46 are located near the inner panel 22 of the door 19 and the front corners of the glass shelves 46 adjacent the air gap between the door 19 and the front edge of the side walls of the food-storage chamber 11 are cut away to provide air passages. It is main-

ly at the front corners of the food-storage chamber 11 that heat leakage into the chamber 11 occurs because of heat leakage through the gasket 24 and through the air gap between the door and the front edge of the side walls of the chamber 11, and because of heat leakage along the heat breaker strips 18 and the adjacent portion of the inner panel 22. The air in this area is also subjected to heat leakage through both the door 19 and the side wall 6 of the food-storage chamber 11.

The corner portions of the rear edges 48 of the shelves 46 extend into the rear corners 16 of the food-storage chamber 11, and the central portions of the rear edges 48 of the glass shelves 46 are cut away to provide air passages at the rear of the inner liner 13. The cut-out area at the rear edges 48 of the glass shelves 46 is directly below the opening in the rear of the cooling unit 26 to provide a downward passage of the cold air issuing therefrom. The rear corners of the glass shelves 46 are carried into the rear corners 16 of the food-storage chamber 11 because the air in these corners is subjected to heat leakage both through the rear wall 7 of the insulated storage chamber as well as through the side wall 6 of the same. It, therefore, is warmer than the adjacent air and would not circulate downwardly vigorously, and for that reason to corner area is more properly reserved for the storage of foods. In the modification of Fig. 4, the air ducts at the glass shelves are thus more nearly located at those areas of the food-storage chamber 11 where the natural convectional air currents are most vigorous.

It will be apparent from the above that this invention provides imperforate shelves in a domestic refrigerator cabinet, which shelves may be transparent and which provide a maximum of shelf surface while providing a minimum obstruction to the natural convectional air currents in the refrigerator and therefore to the cooling action of the cooling unit.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

What I claim is:

1. In a refrigerator cabinet, the combination of insulated top, bottom, and side walls defining a food-storage chamber, one of said side walls having an access opening, an insulated door for said opening, said one side wall, when the door is closed, being of less heat-insulating value per unit of area than any other side wall of said food-storage chamber, a cooling unit in heat exchange relationship with the air in the upper portion of the chamber and a rectangular shelf of continuous solid material below said upper portion of the chamber and spaced from the bottom wall thereof to provide a combined air passage and storage space for foods, said shelf being constructed to provide also an air passage adjacent said door and a further air passage adjacent the central portion of the side wall opposite said door, the shelf having a close fit with the other opposed side walls and preventing the circulation of air past the shelf adjacent the major portions of the width of said last-mentioned opposed walls.

2. In a refrigerator, the combination of a rec-

tangularly-shaped food-storage chamber embodying front, side, rear, top, and bottom heat-insulating walls, said front wall embodying a door opening and a door for said opening, said front wall, when the door is closed, being of lower heat-insulating value per unit of area than any other wall of said chamber, a cooling unit in the upper portion of said chamber, and a substantially rectangular shelf of continuous solid material in said chamber below said cooling unit and spaced from the bottom wall of said chamber to provide a combined air passage and storage space for foods, the front and the rear edges of said shelf being spaced from the front and the rear walls, respectively, of said chamber to provide ducts for the circulation of air, said circulation being downwardly from said cooling unit along the rear wall of said chamber, below said shelf, and upwardly along the front wall of said chamber to said cooling unit, the shelf having a close fit with the side walls and preventing circulation of air past the shelf adjacent the major portions of the width of said side walls.

3. In a refrigerator, the combination of a rectangularly-shaped food-storage chamber embodying front, side, rear, top, and bottom heat-insulating walls, said front wall embodying a door opening and a door for said opening, said front wall when the door is closed, being of lower heat-insulating value per unit of area than any other wall portion of said chamber, a cooling unit in the upper portion of said chamber and extending into close proximity to the rear wall thereof, and a substantially rectangular shelf of continuous solid material in said chamber below said cooling unit and spaced from the bottom wall of said chamber to provide a combined air passage and storage space for foods, the front and the rear edges of said shelf being spaced from the front and the rear walls, respectively, of said chamber to provide ducts for the circulation of air, said circulation being downwardly from said cooling unit along the rear wall of said chamber, below said shelf, and upwardly along the front wall of said chamber to said cooling unit, the shelf having a close fit with the side walls and preventing circulation of air past the shelf adjacent the major portions of the width of said side walls.

4. In a refrigerator, the combination of a rectangularly shaped food-storage chamber embodying front, side, rear, top, and bottom heat-insulating walls, said front wall embodying a door opening and a door for said opening, said front wall, when the door is closed, being of lower heat-insulating value per unit of area than any other wall portion of said chamber, a cooling unit in the upper portion of said chamber, and a substantially rectangular shelf of continuous solid material in said chamber below said cooling unit and spaced from the bottom wall of said chamber, the front and the rear edges of said shelf being spaced from the front and the rear walls, respectively, of said chamber to provide ducts for the circulation of air, said circulation being downwardly from said cooling unit along the rear wall of said chamber, below said shelf, and upwardly along the front wall of said chamber to said cooling unit, the space between the rear wall and the rear edge of the shelf being larger than the space between the front edge of the shelf and the front wall of said chamber, the shelf having a close fit with the side walls and preventing circulation of air

past the shelf adjacent the major portions of the width of said side walls.

5. In a refrigerator, the combination of a rectangularly-shaped food-storage chamber embodying front, side, rear, top, and bottom heat-insulating walls, said front wall embodying a door opening and a door for said opening, said front wall, when the door is closed, being of lower heat-insulating value per unit of area than any other wall of said chamber, a cooling unit in the upper portion of said chamber, and a substantially rectangular shelf of continuous solid material in said chamber below said cooling unit and spaced from the bottom wall of said chamber, the front and the rear edges of said shelf being spaced from the front and the rear walls, respectively, of said chamber to provide ducts for the circulation of air, and the side edges of said shelf being closely adjacent the side walls of said chamber for substantially the entire length of said side edges of said shelf.

6. In a refrigerator, the combination of front, side and back vertical walls and top and bottom horizontal walls defining a rectangular food storage chamber and forming four vertically-extending corners thereof, said front wall comprising a door for closing the food storage chamber and having portions of higher heat conductivity than the back wall and, therefore, having portions of higher temperature than the back wall, a cooling element disposed in the upper portion of the food-storage chamber to cool and induce circulation of air therein, and a generally rectangular imperforate shelf disposed intermediate said horizontal walls and extending substantially flush with the side walls of the food-storage chamber and also substantially to the rear vertical corners thereof, said imperforate shelf, with the front and back walls, forming vertical air passages adjacent the front and rear walls, respectively, whereby the air circulation induced by the cooling element passes downwardly through the air passage adjacent the back wall and upwardly through the air passage adjacent the front wall because of the higher temperature of the front wall.

7. In a refrigerator, the combination of front, side and back vertical walls and top and bottom horizontal walls defining a rectangular food storage chamber and forming four vertically-extending corners thereof, said front wall comprising a door for closing the food-storage chamber and having portions of higher heat conductivity than the back wall and, therefore, having portions of higher temperature than the back wall, a cooling element disposed in the upper portion of the food storage chamber to cool and induce circulation of air therein, and a generally rectangular imperforate shelf disposed intermediate said horizontal walls and extending substantially flush with the side walls of the food-storage chamber and also substantially to the rear vertical corners thereof, said imperforate shelf, with the front and back walls, forming vertical air passages adjacent the front and rear walls, respectively, whereby the air circulation induced by the cooling element passes downwardly through the air passage adjacent the back wall and upwardly through the air passage adjacent the front wall because of the higher temperature of the front wall, said cooling element having front and back portions adjacent the front and back walls of the chamber, respectively, the back portion of the cooling element being in better heat conducting rela-

tionship with the air adjacent the back wall than the front of the cooling element with the air adjacent the front wall, so that air circulation downwardly through said air passage adjacent the back wall is assisted.

8. In a refrigerator, the combination of front, side and back vertical walls and top and bottom horizontal walls defining a rectangular food-storage chamber and forming four vertically-extending corners thereof, said front wall comprising a door for closing the food-storage compartment and having portions of higher heat conductivity and, therefore, at a higher temperature than the back wall, a cooling element disposed in the upper portion of the food-storage chamber to cool and induce circulation of air therein and a plurality of spaced, generally rectangular imperforate shelves disposed intermediate said horizontal walls and extending substantially flush with the side walls of the food-storage chamber and also substantially to the rear vertical corners thereof, each of said imperforate shelves, with the front and back walls, forming vertical air passages adjacent the front and rear walls, respectively, whereby the air circulation induced by the cooling element passes downwardly through the air passages adjacent the back wall and upwardly through the air passages adjacent the front wall because of the higher temperature of the front wall.

9. In a refrigerator cabinet, the combination of insulated front, side, rear, top, and bottom walls forming a rectangular food-storage chamber, said front wall having a door opening therein, a door for said opening, at least one edge of said opening and one edge of said door forming a vertical joint of relatively low heat-insulating value, a cooling unit in the upper portion of said chamber near the rear wall but spaced from the side walls thereof, and a substantially imperforate shelf in said chamber, said shelf having side edges extending contiguously along the side walls of said chamber, said shelf being spaced from said vertical joint to define an air-circulating opening adjacent thereto and spaced also from the central portion of the rear wall to define a second air-circulating opening, whereby the convectional air currents in the food storage chamber circulate downwardly in said second-named air-circulating opening and up-

wardly in said first-named air-circulating opening.

10. In a refrigerator cabinet, the combination of insulated front, side, rear, top, and bottom walls forming a rectangular food-storage chamber, said front wall having a door opening therein, a door for said opening, at least one edge of said opening and one edge of said door forming a vertical joint of relatively low heat-insulating value, a cooling unit in the upper portion of said chamber and spaced from the side walls thereof, said cooling unit making more intimate contact with the air in the rear portion of the storage chamber than with the air in the front portion thereof, and a substantially imperforate shelf in said chamber, said shelf being spaced from said vertical joint to define an air-circulating opening adjacent thereto and spaced also from the central portion of the rear wall to define a second air-circulating opening, whereby the convectional air currents in the food-storage chamber circulate downwardly in said second-named air-circulating opening and upwardly in said first-named air-circulating opening.

11. In a refrigerator, the combination of an insulated, rectangularly-shaped food-storage chamber embodying front, rear, and side vertical walls, and horizontal top and bottom walls, one of said vertical walls being of lower heat-insulating value than any other vertical wall of equal area of said chamber, a cooling unit in the upper portion of said chamber, and a substantially rectangular shelf of continuous solid material in said chamber below said cooling unit and spaced from the bottom wall of said chamber to provide a combined air passage and storage space for foods, said shelf being also spaced from said vertical wall of lower heat-insulating value and from another of said vertical walls opposite said walls of lower heat-insulating value, the spaces between said shelf and said first opposed vertical walls and the space below said shelf providing ducts for the circulation of air around said shelf, said circulation being upwardly along the wall of lower heat-insulating value of said chamber, the shelf having a close fit with the other opposed vertical walls and preventing circulation of air past the shelf adjacent the major portion of the width of said walls.

JOHN H. ASHBAUGH.

CERTIFICATE OF CORRECTION.

Patent No. 2,343,166.

February 29, 1944.

JOHN H. ASHBAUGH.

It is hereby certified that error appears in the printed specification of the above numbered patent requiring correction as follows: Page 2, second column, line 30, for the word "to" before "corner" read --the--; page 4, second column, line 41, claim 11, for "walls" read --wall--; line 48, same claim, for "calls" read --walls--; line 50, same claim 11, after "said walls." and before the signature insert the following claims -

--12. In a refrigerator cabinet, the combination of first, second, third, and fourth vertical walls and two horizontal walls joined together to form a rectangularly-shaped food-storage chamber having said first and second wall opposite to one another, said first vertical wall being of higher heat-insulating value than said second vertical wall, a cooling unit in heat exchange relationship with the air in the upper portion of said chamber, and a substantially rectangular, imperforate, and horizontal shelf in said chamber below said cooling unit and extending substantially to the third and fourth vertical walls and substantially from corner to corner of the food-storage chamber except for small spaces adjacent said first and second vertical walls, said shelf being spaced from the first and second vertical walls of the cabinet to define an air passage adjacent each of said first and second walls, whereby the air in said cabinet is chilled by the cooling unit and circulates downwardly through the air passage adjacent said second wall, passes below the shelf, and circulates upwardly through the air passage adjacent said first wall and passes above the shelf to said cooling unit.

13. In a refrigerator comprising an insulated chamber having front, side, and rear vertical walls, a top and a bottom wall, said front wall being of lower heat insulating value per unit of area than said side and rear walls, and a cooling unit in the upper portion of said chamber, the combination of an imperforate and approximately rectangular shelf in said chamber below said cooling unit and spaced from said bottom wall to provide a combined air passage and storage space in said chamber, said shelf having front, side, and rear edges, at least a portion of said front edge being spaced from the front wall and at least a portion of said rear edge being spaced from the rear wall of said chamber to provide an air passage adjacent said front and adjacent said rear wall, the side edges of said shelf lying adjacent the respective side walls of said chamber. --;

in the heading to the printed specification, line 8 thereof, for "11 Claims" read --13 Claims--; and that the said Letters Patent should be read with this correction therein that the same may conform to the record of the case in the Patent Office.

Signed and sealed this 25th day of April, A. D. 1944.
